COMBINED CHAIR AND TABLE

Fred W. Luckman, Chicago, Ill., assignor to Home Equipment Manufacturing Co., Chicago, Ill., a corporation of Illinois

Application September 8, 1949, Serial No. 114,656

2 Claims. (Cl. 155—123)

1

My present invention relates to a combination chair and table construction, and is more particularly directed to a table having an opening in the top thereof in which a chair is adapted to be disposed.

It has heretofore been proposed to provide a combination chair and table construction of the character indicated in which the chair is adapted to be removably mounted in the table. It has been further contemplated to provide in such construction for the pivotal mounting of the chair so that an infant may swing while seated at the table. A disadvantage of known constructions in the latter respect resides in the complexity of the parts utilized for the purpose. The construction referred to usually comprises a plurality of interconnected links and obviously such constructions are bulky, complicated and expensive, and furthermore makes it a difficult and tedious task to remove the chair from the table. A further disadvantage of known devices is that the chairs cannot readily be fixed against swinging movement about their pivotal axes as is desired, for example, when an infant is to be fed at the table.

An object of my present invention is to provide a table having an opening in the top thereof, and a chair adapted to be removably mounted therein, and which chair is adapted to be selectively supported in pivotal or fixed relation to the table when mounted therein.

Another object of my invention is to provide means for positively locating the chair in various positions lengthwise of the table, independent of whether the chair is mounted pivotally or fixedly.

A further object of my invention is to provide the chair with a foot rest assembly having strap members pivotally secured within outwardly facing recesses formed in each side of the chair in such a manner so as to keep the outwardly facing sides of the strap members from extending laterally beyond vertical planes passing through each of the outwardly facing surfaces of the sides of the chair.

Now in order to acquaint those skilled in the art with the manner of constructing and using devices embodying my invention, I shall describe in connection with the accompanying drawings, a preferred embodiment of my invention.

In the drawings:

Figure 1 is a perspective view of a combination chair and table of my present invention in erected position;

Figure 2 is a plan view of the combination chair and table shown in Figure 1;

2

Figure 3 is a vertical lengthwise sectional view taken along the line 3—3 of Figure 2 looking in the direction indicated by the arrows;

Figure 4 is a vertical lengthwise sectional view taken along the line 4—4 of Figure 2 looking in the direction indicated by the arrows;

Figure 5 is a vertical transverse sectional view taken substantially along the lines 5—5 of Figure 2, looking in the direction of the arrows; and

Figure 6 is a partial vertical transverse sectional view taken along the lines 6—6 of Figure 2 looking in the direction indicated by the arrows.

Referring now to Figure 1, there is shown a table, indicated generally by the reference numeral 10, and a chair, indicated generally by the reference numeral 11. The table 10 comprises a frame having a pair of parallel vertical lengthwise extending side frame members 12 and 13, joined at their ends by a pair of parallel vertical transversely extending rear and front frame members 14 and 15 respectively. Provided adjacent each of the four corners of the frame are foldable legs, of which only three are shown, as at 16, 17 and 18. The legs are hinged to the table 10 as by hinges 19 which are of known construction, and for example, may be of the form used on conventional card tables. Hinges of this character permit the legs to nest within the sides 12, 13, 14 and 15 when the table is not in use. The legs 17 and 18 disposed adjacent the front of the table 10 are provided with casters 19 and 20, respectively. The rear legs, of which only one is shown at 16, are preferably not provided with casters, and are of the same height as the front legs 17 and 18, including their casters 19 and 20.

The top of the table 10 comprises a pair of parallel horizontal lengthwise extending panel members 21 and 22, one disposed adjacent each side of the table 10, and a horizontal slidably panel member 23, which is disposed at the central front portion of the table 10. The panels are preferably fabricated from a hard surfaced material, as for example "Masonite." As will be noted, an opening is thus provided at the central rear portion of the table 10 for accommodating the chair 11. The front transverse frame member 15 is provided with a horizontal slot 24, through which the slidable panel member 23 is adapted to extend for a purpose to be herein-after described. Disposed lengthwise along opposite sides of the opening formed in the top of the table 10 are a pair of guide rails 25 and 26, as best shown in Figures 2 and 5. The

forward end portions of the guide rails 25 and 26, are each formed with an inwardly facing lengthwise extending groove, of which one is shown at 27, in the rail 25, in Figure 6. The panel members 21 and 22 are secured along their inner edges to the upper surfaces of the guide rails 25 and 26, as by a plurality of screws 28, as shown in Figures 1 and 2. It will be observed that the inner edges of the panel members 21 and 22 terminate short of the inner edge of the rails 25 and 26 to provide for the slidable support by the latter of the outer edge portions of the slidable panel member 23. The outer edges of the slidable panel member 23 are disposed closely adjacent the inner edges of the side panels 21 and 22 so that the upper surfaces of these several panels lie substantially in a common plane. Secured adjacent the rearward edge of the slidable panel member 23 is a slidable guide member 29 having a tongue portion 30 at the end thereof adjacent guide rail 25, as shown in Figure 6, which is adapted to engage slidably with the groove 27 in the guide rail 25. A similar tongue portion is formed on the other end of the guide member 29 and is adapted to engage slidably in a groove, like groove 27, formed in the adjacent guide rail 26. The forward edge of the guide member 29 is recessed at 31, as shown in Figure 2, for receiving the rearward edge of the slidable panel member 23, which is secured thereto, as by screws 31'. The frame members 12, 13, 14 and 15 project above the surface of the horizontal panel members 21, 22 and 23 for preventing accidental sliding off of dishes or toys that may be placed on the table.

The chair 11, disposed in the opening formed in the top of the table 10, as shown in Figure 1, comprises a seat portion 32, side frames 33 and 34 having pairs of oppositely aligned vertical grooves 35 and 38 formed adjacent the rear portions thereof, and a back portion 36, which is adapted to be selectively disposed in either pair of grooves 35 or 38. The side portions 33 and 34 are held in parallel relation by means of a transverse rod 37 extending therebetween. Recesses 47 and 48 are formed in the lower forward corners of outwardly facing sides of side frames 33 and 34, for a purpose which will hereinafter be described.

The seat 11 is provided with a foot rest assembly, indicated generally by the reference numeral 45 as shown in Figures 3 and 4, comprising downwardly depending angle iron strap members 49 and 50, which are pivotally secured at their one ends, one adjacent each side of the seat 11 within the aforementioned recesses 48 and 49. The strap members 49 and 50 are secured in such a manner as to keep their outwardly facing sides from extending laterally beyond vertical planes passing through each of the outwardly facing surfaces of the sides of the chair. The foot rest assembly 45 is mounted to the chair 11 in this manner so that the strap members 49 and 50 do not catch on the upper panel members 21 and 22 when the chair and foot rest assembly are being withdrawn from the opening in the top of the table. Also, the opening need not be formed wider than substantially the width of the chair, thereby providing a neat appearing device. Extending between the strap members 49 and 50, and secured thereto, is a riser member 51, and pivotally secured to the outwardly facing sides thereof, are flange members 52 and 53 which may, for example, be fabricated from sheet metal. Extending

between the flange members 52 and 53 and secured thereto is a kick board 46.

The means for supporting the chair 11 in the opening of the table comprises a pair of pins 39, 5 one each projecting laterally outwardly from each side of the chair 11, as shown in Figure 2. Formed in each inwardly facing side of the guide rails 25 and 26, intermediate of the ends, is a vertical slot 40 open at its upper end, one of 10 which is shown in Figures 3 and 4. Depending from the lower portion of each slot 40 is a horizontal slot 41 having notches 42 formed in the lower edge at each end thereof. The slots 40 and 41 are adapted to receive the free ends of the pins 39, thus forming a pivotal support for the chair 11.

Formed in the inwardly facing side of the guide rail 25, adjacent the rear end thereof, is a horizontal groove 43, as shown in Figures 3, 4 and 5, 20 which is adapted to selectively receive the free end of a laterally shiftable pin 44 disposed in an aperture formed in the side 34 of the chair 11 adjacent the rear thereof.

The table and chair are preferably fabricated 25 from wood with the exception of parts noted otherwise.

In assembling the chair and table of my present invention, the following procedure is followed:

30 Each of the legs of the table 10 is disposed in an erect position as shown in Figure 1 and the shiftable panel member 23 is drawn outwardly through slot 24 so as to permit the chair 11 to be disposed within the opening formed in the top 35 of the table 10. The chair 11 is then held above the opening in the table 10 and lowered so as to enable the pins 39 to slide vertically downward along the vertically extending grooves 40 formed in the guide rails 25 and 26, until the pins 39 40 fit into the horizontally extending grooves 41. The pins 39 are then selectively seated in either pair of notches 42, formed in the lower edges of the horizontal slots 41, which notches provide for the positive locating of the chair 11 lengthwise with respect to the table.

45 After a child is seated in the chair 11, the shiftable panel member 23 may be pushed inwardly, with its inner edge as close to the child as desired. The chair in the above described position, 50 is adapted for rocking movement, of which two positions are shown by the dotted and solid lines of the chair 11 in Figure 4. Should it be desired to hold the chair rigid, as would be the case when the child is eating, the pin 44 disposed in the side 55 of the chair 11 at the rear portion thereof, is shifted laterally outwardly so as to engage with the groove 43 formed in the inwardly facing side of the guide rail 25.

When the chair 11 is to be removed from the 60 table 10 and it is in its fixed position, the pin 44 is shifted inwardly out of engagement with the groove 43. The chair 11 is shifted forward so as to dispose the pins 39 at the bottom portion of the vertically extending groove 40, and then upward therefrom.

65 If it is desired to store the table 10 with the chair 11 disposed therein, the foot rest assembly 45 may be swung upward from the position shown in Figure 4 to the position shown in Figure 3, and the flanges 52 and 53 and the kick board 46 may be further folded about the point 60 to a position, not shown, with the kick board 46 substantially parallel to the strap members 49 and 50. The legs may then be folded up in the conventional manner.

5

While I have shown what I consider to be a preferred embodiment of my invention, it will be understood that various modifications may be made therein without departing from the spirit and scope of my invention.

I claim:

1. In combination, a table having an opening in the top thereof, guide rails extending lengthwise along opposite sides of the opening, a legless chair having a rigid seat with rigid sides secured thereto, means between the sides of said chair and said guide rails for detachably supporting said chair in depending relation within the opening of said table, said sides of said chair having recesses formed in the outwardly facing surfaces of the chair, and a foot rest assembly having a strap member pivotally secured at one end within each of said recesses with the outwardly facing sides of each of said strap members not extending laterally beyond vertical planes passing through each of the outwardly facing surfaces of the sides of said chair, whereby said chair and foot rest assembly are adapted to be removed upwardly through the opening of said table.

2. In combination, a table having an opening in the top thereof, a legless chair having a rigid seat with rigid sides secured thereto, means be-

tween the sides of said chair and said table for detachably supporting said chair in depending relation within the opening of said table, said sides of said chair having recesses formed in the outwardly facing surfaces of the chair, and a foot rest assembly having a strap member pivotally secured at one end within each of said recesses with the outwardly facing sides of each of said strap members not extending laterally beyond vertical planes passing through each of the outwardly facing surfaces of the sides of said chair, whereby said chair and foot rest assembly are adapted to be removed upwardly through the opening of said table.

FRED W. LUCKMAN.
